UNITED STATES PATENT OFFICE.

PETER B. MATHIASON, OF ST. LOUIS, MISSOURI.

BRICK-MACHINE.

SPECIFICATION forming part of Letters Patent No. 331,420, dated December 1, 1885.

Application filed October 20, 1884. Serial No. 146,008. (No model.)

To all whom it may concern:

Be it known that I, PETER B. MATHIASON, of the city of St. Louis, in the State of Missouri, have invented a certain new and useful improvement in Brick-Machines, of which the following is a full, clear, and exact description, reference being had to the accompanying drawings, forming part of this specification, and in which—

10 Figure 1 is a side elevation of a brick-machine embodying my improvements. Fig. 2 is a front end view. Fig. 3 is a top or plan view. Figs. 4 and 5 are diagrams illustrating different positions of the parts during the operation of the machine. Fig. 6 is a vertical section taken on line 6 6, Fig. 3. Fig. 7 is a horizontal section taken on line 7 7, Fig. 6; and Fig. 8 is a detail horizontal section taken on line 8 8, Fig. 6.

20 My invention relates to certain improvements in brick-machines; and it consists in features of novelty hereinafter fully described, and pointed out in the claims.

Referring to the drawings, A represents the 25 frame of the machine, having a table, A', (see Fig. 6,) with an opening in which is secured a mold, A².

B represents an upper plunger, and C a lower plunger, for pressing the clay to form the 30 bricks.

I have shown a four-part mold and four-part plungers, (see Figs. 2 and 7,) the compartments of the mold being marked A³, and the four parts of the plungers marked B' and C', respectively. Four bricks can thus be 35 made at once; but these parts may be increased or diminished in number, as desired.

The mold is filled by a charger, D, sliding over the table A' and supported by and sliding on rods D', that pass through perforations in lugs D², formed upon or secured to the charger. (See Fig. 6.) The rods are supported by hangers D², depending from the upper part of the frame of the machine. The 40 charger is operated by an arm, D⁴, on a shaft, G, to which it is connected by links or pitmen D⁵. The arm is fixed upon the shaft, and the shaft is journaled in boxes secured to the frame of the machine. The arm is preferably inside 45 of the frame, as shown in Figs. 1, 6, and 7.

Secured to the shaft, and extending toward

the front end of the machine, is a lever, H, preferably outside of the frame, as shown in Figs. 2, 3, 4, 5, and 7. The forward end of this lever has a slot, H', to receive a driving-shaft, I, on which is a cam, I', to force the charger backward by rocking the shaft G, and cams I² for forcing the charger forward. As the shaft I revolves, the cams I² bear against friction-rollers I³, on the lever, and by lowering its inner end, as shown in Fig. 5, force the charger forward, and then, as the shaft continuous to revolve, the cam I' comes against a friction-roller, I⁴, on the lever, (see Fig. 2,) and by raising its inner end, as shown in Fig. 4, 60 pulls the charger back. The shaft I is journaled in boxes secured to the frame, and is turned by any suitable means. As a means for turning it, I have shown a cog-wheel, I⁵, thereon, engaged by a worm, I⁶, (see Figs. 1, 70 2, and 3,) on a shaft, I⁷, journaled in boxes I⁸, secured to the frame and provided with a driving-pulley, I⁹.

J L represent upper and lower rock-shafts journaled in the frame, and to which the upper and lower plungers are respectively connected by toggle-arms J' and L'. To these toggle-arms are connected toggle-bars M and N, which are also connected to the frame of the machine by pivot-pins or shafts M' N'. 80 The toggle-bars of the upper and lower plungers are connected at their centers, where they are hinged together, by links O. As the centers of these toggle-bars are pulled downward, it will be seen that the centers of the toggle-bars J' L' will be forced forward in the direction indicated by the arrows, Fig. 1, which will cause the plungers to be forced toward each other to the position shown in Fig. 6, thereby pressing the clay within the mold, 90 forming the brick. This movement is caused by cams P on the shaft I, that, as the shaft turns, come against projections R, which may have friction-rollers R', if desired, on extensions N² of one pair of the toggle-bars, N. The 95 extensions have slots N³, that receive the shaft I, and the cams P fit between them. The friction-rollers R', are journaled on pins R², passing through the projections R. (See Fig. 2.) On the shaft I, between the cams P, is another 100 cam, S, that, after the plungers are forced together, as described, comes against a fric-

tion-roller, T, on a pin, T', passing through the extensions of the toggle-bars, and forces the parts back from the position shown in Fig. 6 to that shown in Fig. 1. The parts are so arranged and adjusted that the charger makes its forward movement, deposits the clay into the mold, and moves back from over the mold while the plungers are held apart by the cam S, and then the cams P come into operation and move plungers toward each other, as described. The plungers are guided and held in position by fitting in openings A⁵ in the frame, and by rods A⁶, that pass through perforations therein and in the top and bottom of the frame, tying the frame together vertically. Tie-rods A⁷ strengthen and support the frame horizontally.

When the bricks are pressed and the cam S comes into operation to cause the plungers to move apart, as described, the lower plunger, instead of receding at once with its operating mechanism, is made to move upward with the upper plunger a short distance to eject the bricks by means of bell-crank levers U, secured to a rock-shaft, U', journaled in boxes secured to the frame of the machine. (See Figs. 1, 6, and 8.) The outer ends of these levers fit beneath the plunger, and they are operated to lift the plunger, when the pressing is done, by cams U² on the shaft I, which come against friction-rollers U³ on pins U⁴, projecting from the levers.

I do not claim to be the inventor of the broad idea of pressing the bricks by one mechanism and then by means of another mechanism causing the lower plunger to follow the upper one until the bricks are out of the mold, as the same is shown and described in English Patent No. 949 of 1860.

40 In order that the lower toggle-arms, L', will not interfere with this raising of the lower plunger, I form yokes L⁴ on one pair of the arms L', that fit over the connecting - pin L⁵. (See Fig. 6.) The yokes being open at their lower ends, clay and dirt will not gather there, as it would were they closed, which, if not kept well cleaned out, would interfere with the free and full operation of the parts. When the cams S have passed the levers, the

50 plunger drops to its lower position, where it rests upon a U-shaped frame, V, pivoted by its inner ends at V' to the frame A, while its outer end rests upon the upper ends of set-screws W, fitting in boxes W', secured to the frame A, which are screw-threaded to receive them. Fitting over the screws, above the threads and between the two parts of the boxes, (see Fig. 6,) are worm - blocks W², having feather-and-groove connection with the screws, 60 into which meshes a threaded shaft, W³, journaled in boxes W⁴, secured to the frame A. The shaft has a hand wheel or crank, W⁵, on one or both ends, preferably both, as shown, by which it can be turned to raise and lower the frame V, to regulate the fall of the plunger and the consequent amount of clay entering the mold—the plunger never falling beneath

the bottom of the mold—and thus bricks of a uniform thickness may be obtained. The sides of the frame preferably have raised parts or 70 projections W⁶ to receive the plunger.

It will be seen that there are no side strains whatever on the working parts of my machine. Where there is a single cam it has a central bearing, and where there are two cams operating together they bear on corresponding parts of the thing operated upon—as, for instance, the cam I' bears against the center of the lever H, and the cams I' against its outer edges, the cam S has central bearing on the 80 extensions N², and the cams P corresponding bearings on the outer parts of the extensions, and so on.

Each pair of the bars M and N may be connected by cross-pieces, if desired, as shown at 85 M', Fig. 3.

I claim as my invention—

1. The combination of a charger formed with upwardly-extending perforated lugs, hangers, and rods passed through the hangers and lugs 90 for supporting the charger above the table, substantially as set forth.

2. The combination, with a charger suitably mounted, and a rock-shaft to which it is connected, of a driving-shaft provided with three cams and a slotted lever having friction-rollers and secured to the rock-shaft, the driving-shaft fitting in the slotted lever, and the cams bearing on the friction-rollers to elevate and depress the lever, causing the advance and retraction of the charger, substantially as set forth. 95

3. The combination, with upper and lower plungers and the toggle-arms by which the plungers are operated, of the upper and lower toggle-bars hinged to the frame and toggle-arms, and devices by which the latter are elevated and depressed, substantially as set forth. 100

4. The combination, with upper and lower plungers and the toggle-arms by which the 110 plungers are operated, of the upper and lower toggle-bars hinged to the frame and toggle-arms, link connecting the toggle-bars, and devices by which the latter are elevated and depressed, substantially as set forth. 115

5. The combination, with upper and lower plungers and the toggle-arms by which the plungers are operated, of the upper and lower toggle-bars hinged to the frame and toggle-arms, link connecting the toggle-bars, a driving-shaft having cams, and an extension to the 120 toggle-bars connecting the latter with the cams by which they are elevated and depressed, substantially as set forth.

6. The combination, with upper and lower 125 plungers and the toggle-arms by which the plungers are operated, of the upper and lower toggle-bars hinged to the frame and toggle-arms, link connecting the toggle-bars, a driving-shaft having cams, and a slotted extension 130 to a lower toggle-bar having projections provided with friction-rollers, substantially as set forth.

7. The driving-shaft I, having cams I' and

I², for operating the charger-connections, cams P and S, for operating the plunger-connections, and cams U², for operating the bell-crank lever, which continues the upward movement of 5 the lower plunger with that of the upper plunger, substantially as set forth.

8. The combination, with the plunger and charger connections, of the driving-shaft provided with cams I' and I² and cams P and S, 10 substantially as set forth.

9. The combination, with the upper and lower plungers, the toggle-arms by which the plungers are operated, a charger suitably mounted, and a rock-shaft to which the charger 15 is connected, of the toggle-bars by which the toggle-arms are hinged to the frame, link connecting the toggle-bars, extension to the toggle-bars, lever secured to the rock-shaft, and a driving-shaft having cams P and S, embraced 20 by the extension, and cams I' and I², embraced by the lever, substantially as set forth.

10. The lower plungers having toggle-arms formed with open yokes, substantially as set forth.

11. The combination of the perforated upper and lower plungers, perforated frame, and tie-rods passing through the plungers and tying the frame together, substantially as set forth. 25

12. The combination, with the falling lower plunger, of the U-shaped frame adjustable 30 thereunder, substantially as set forth.

13. The combination, with the falling lower plunger, of the U-shaped frame having raised portions to receive the plunger and adjustable as to height, substantially as set forth. 35

14. The combination, with the falling lower plunger, of the U-shaped frame hinged to the main frame, and the means for adjusting the U-shaped frame, comprising set-screws having worm-blocks and secured to the main 40 frame, and a threaded shaft by which the set-screws are adjusted, substantially as set forth.

PETER B. MATHIASON.
